FRANCIS PIDJEON, OF SAUGERTIES, NEW YORK.

Letters Patent No. 70,606, dated November 5, 1867.

IMPROVED RAIL-CLAMP JOINT.

The Schedule referred to in these Letters Patent and making part of the same.

TO ALL WHOM IT MAY CONCERN:

Be it known that I, FRANCIS PIDJEON, of Saugerties, in the county of Ulster, and State of New York, have invented a new and improved "Rail-Joint Clamp;" and I do hereby declare that the following is a full, clear, and exact description thereof, which will enable others skilled in the art to make and use the same, reference being had to the accompanying drawings, forming part of this specification.

The present invention consists, first, in a dove-tail-shaped clamp, thereby dispensing with all bolts, and allowing the rail to contract or expand by heat or cold; second, in bringing the weight of the train, when passing over the joint to and upon the flat bottom to the rail, by carrying the clamp upon the outside of the rail up even with the top of the rail; third, in forming the rail with a flat bottom-piece, for the purpose of taking the bearing in a better manner than with the ordinary form of rail; fourth, in giving a dove-tail shape to the rails at and near each end, to receive a dove-tail-shaped clamp. In the accompanying plate of drawings my improved rail-joint clamp, &c., is illustrated—

Figure 1 being a plan or top view of the same, and

Figure 2 a transverse vertical section, taken in the plane of the line x x , fig. 1.

Similar letters of reference indicate like parts.

A, in the drawings, represents the two ends contiguous to each other of rails B. These rails are made with flat bottom-pieces C, and at their contiguous ends, where to be jointed, are made dove-tail-shaped at E, so as to receive the dove-tailed-shaped sides F of the two portions G and H to the clamp for the joint, of which clamp G is the outside portion, and is extended up to and on a level with the surface of the rails B.

By the construction of the rail and clamp described above in detail, it is plainly obvious all the objects herein previously stated are secured, and in a most effectual and practical manner.

Having thus described my invention, what I claim as new, and desire to secure by Letters Patent, is—

1. The combination of the dove-tailed rails E and dove-tailed clamps G H, substantially as described, for the purpose specified.

2. In combination with the above, the outer section of the clamp flush with the head of the rail, substantially as described, for the purpose specified.
